UNITED STATES PATENT OFFICE.

HARRY HENRY LEECE, OF PORTLAND, OREGON.

DEVICE FOR CHALKING CUES.

1,114,490.

Specification of Letters Patent. Patented Oct. 20, 1914.

Application filed February 28, 1914. Serial No. 821,839.

To all whom it may concern:

Be it known that I, HARRY HENRY LEECE, a citizen of the United States, and a resident of Portland, in the county of Multnomah and State of Oregon, have invented an Improvement in Devices for Chalking Cues, of which the following is a specification.

My present invention relates to billiard room accessories, and more particularly to a cue chalking device.

One of the principal objects of the invention is to provide a device which may be attached to a suitable portion of a billiard table, and which may be used to automatically chalk the billiard cue tips.

Another object of the invention is to provide a device of the class described embodying means whereby the chalk dust may be caught and delivered to a suitable receptacle.

A further object of the invention is to provide a device such as described and embodying means for rotatably supporting a block of chalk, and means whereby upon pressing the cue tip upon the block, the latter will be automatically rotated for coating the cue tip with chalk.

A still further object of the invention is to provide a device of the class described, which will be simple, durable, efficient in operation and inexpensive to manufacture.

With these and other objects in view which will become apparent as the description proceeds, the invention resides in the construction, combination, and arrangement of parts hereinafter more fully described and claimed, and illustrated in the accompanying drawing in which like characters of reference indicate like parts throughout the several figures, of which,

Figure 1 represents a side elevational view of the device as positioned ready for use. Fig. 2 represents a vertical transverse sectional view taken on the plane indicated by the line 2—2 of Fig. 1, looking in the direction indicated by the arrows. Fig. 3 represents a horizontal sectional view taken on the plane indicated by the line 3—3 of Fig. 2.

Referring more particularly to the drawing, 5 represents the hollow tubular body, closed at its lower end by a circular block 6 threaded into the tube, and provided at its upper end internally, with an externally threaded nipple 7, for receiving a guide cap 8, of a diameter equal to the diameter of

tube 5. A partition 9 is positioned transversely of the tube near the upper end thereof, and is provided axially of the tube with a lug on block 10, which forms a bearing for a shaft 11, provided with a spiral groove 12, engaged by a lug 13 on block 10, and said shaft is adapted to travel through the block in order to give a rotary motion to the shaft. On the upper reduced end of the shaft 11 is threaded a chalk clamp 14 providing a plurality of spring clips 15 for holding a block of chalk, illustrated as 16.

Extending centrally and axially of the tube, between partition 9 and block 6, is a spring tube 17, provided at its lower end with a flange 18 connected by means of bolts 19 to block 6, for holding the spring tube in place. Positioned in tube 17 is a coiled spring 20 supporting at its upper end a substantially frusto-conical thrust block 21 which snugly fits the tube, and which is provided with a stem 22 projecting into the convolutions of spring 20. Shaft 11 is provided at its lower end with a disk or plate 23 which also snugly fits tube 17, and which rests upon thrust block 21, said block by action of spring 20, normally holding the shaft in the position shown, with the plate 23 bearing against the under side of block 10, and with the chalk 16 in its outermost position, ready to receive a cue tip illustrated as 24. It will be readily understood that by bearing upon the cue tip, the shaft 11 will be rotated, and will descend against the tension of spring 20, the chalk being rotated with the shaft, thus thoroughly coating the cue tip with chalk. Upon retracting the cue tip from the block, the shaft will be thrust outwardly, by reason of spring 20, into the position shown.

The guide cap 8, is provided with a substantially conical flange 25, open at the bottom end, and depending within cap 8 from the upper edge thereof, the purpose of said flange being to guide a cue when projected into the device, so as to center the cue tip upon the chalk block 16. The upper end of the body tube 5, is encircled by a band 26 provided at each end with feet of webbed portions 27, whereby to form a clamp bracket for securing the device to a suitable support such as the leg or side of a billiard table. A second supporting bracket may be provided, which comprises a disk 28 secured to block 6 by means of bolts 19, and also pro-

vided with a foot portion 29, extending at right angles to disk 28 and in parallel relation to the tube.

In order that the dust formed incident to the chalking of the cue tips, may be collected, the dust pan 30 is provided, which is hinged as at 31 between a pair of lugs formed on the body 25. The dust pan is open on one side, and is held with that side directed 10 against the body tube, by means of a spring catch 33 secured in place upon disk 28 by means of the bolts 19, and the portion of body tube 5 lying between the side walls 34 of the dust pan, is perforated as at 35 to 15 allow the exit of dust from the tube into the dust pan, which dust is allowed to fall into the body tube 5 around the spring tube 17 from the portion of the tube above partition 9, by reason of an opening 36 formed in said 20 partition. By this construction it will be apparent that the dust formed will drop through opening 36 into the lower end of body tube 5 and as it accumulates, will be deposited in the dust pan 34, which may be 25 emptied when necessary.

Although I have described the preferred embodiment of my invention, I may desire to make such changes in the construction, combination and arrangement of parts 30 thereof, as do not depart from the spirit of the invention, and the scope of the appended claims.

I claim:

1. A device of the class described, comprising a body tube, a block positioned at one end thereof for closing the same, a partition positioned transversely of the tube, a spring tube of smaller diameter than the body tube positioned centrally and 35 axially of said body tube, and extending between said partition and said block, a coil spring positioned within said spring 40 tube.

tube, a thrust block supported by said coil spring, a bearing formed on said partition, a shaft extending through said bearing and 45 provided with a plate positioned in the spring tube, and adapted to rest against said thrust block, said shaft provided with a spiral groove, said bearing provided with a lug extending into said groove, a chalk 50 holder secured to the end of the shaft opposite the plate, a guide cap detachably secured to said body tube, said cap comprising a tube having a conical flange portion depending within the tube from its upper end, 55 said flange portion adapted to form a guide for projecting a billiard cue tip on to a lump of chalk supported by said chalk holder, and means for collecting the dust formed incident to the chalking process. 60

2. A device of the class described, comprising a body tube closed at one end, a partition arranged transversely of the tube, a spring tube positioned within the body tube between the closed end and said partition, means for maintaining a block of chalk above the partition, for automatically chalking a billiard cue when projected against the chalk, and means for collecting the chalk dust, said means comprising a dust pan 70 hinged to said body tube near the lower end thereof, said pan being open on one side and adapted to have said side closed by the said body tube, a spring clip for normally securing pan in closed position, said body tube 75 provided with perforations communicating with the said pan, said partition provided with an opening for allowing entrance of chalk dust into the lower end of the body tube.

HARRY HENRY LEECE.
